Bernard Darvie, New York, N. Y.

Application December 21, 1945, Serial No. 124,927

Term of patent 3½ years

(Cl. D45—19)

To all whom it may concern:

Be it known that I, Bernard Darvie, a citizen of the United States of America, residing in New York city, county of New York, and State of New York, have invented a new, original, and ornamental Design for a Brooch or Similar Article, of which the following is a specification, reference being had to the accompanying drawing, forming part thereof.

Fig. 1 is a plan view of a brooch or similar article, showing my new design.

Fig. 2 is an edge view thereof.

I claim:

The ornamental design for a brooch or similar article, substantially as shown.

BERNARD DARVIE.
